UNITED STATES PATENT OFFICE.

WALTER BIBBEE, OF SPOKANE, WASHINGTON.

INTERNAL-COMBUSTION ENGINE.

1,278,836.

Specification of Letters Patent. Patented Sept. 17, 1918.

Application filed May 7, 1917. Serial No. 186,908.

To all whom it may concern:

Be it known that I, WALTER BIBBEE, a citizen of the United States, and a resident of Spokane, in the county of Spokane and State of Washington, have invented new and useful Improvements in Internal-Combustion Engines, of which the following is a specification.

My invention is an improvement in internal combustion engines, and has for its object to provide mechanism adapted to be arranged between the carbureter and the air inlet, for straining and purifying air before it enters the carbureter.

15 In the drawing is shown a vertical section showing the improvement in place.

The present embodiment of the invention is shown in connection with a carbureter 1, and the improvement comprises a substantially cylindrical casing 2, having at its upper end an outlet, connected with the carbureter 3 by means of a pipe 4. Near its lower end the casing has an inlet pipe 5 for the air, the said pipe having an elbow at 25 its inner end, and the elbow opens upward in alinement with the pipe 4. A cylindrical sleeve or shell 6 is arranged within the casing 2 near its lower end, coaxially with the casing and spaced apart therefrom, and the pipe 5 passes through this casing, the casing extending above and below the pipe.

A conical divider or distributor 7 is arranged above the open end of the pipe 5, and with the lower or larger end of the deflector 35 below the upper end of the pipe, and this deflector is connected to the shell 6 by a screen 8, the said screen being frusto-conical, and connected at one end with the base of the deflector, and at the other with the top 40 of the shell. Between the lower end of the sleeve 6 and the casing is arranged a second screen 9, this screen closing the space between the shell and the casing.

A water supply pipe 10 leads into the casing above the deflector 7, and delivers at the apex of the deflector with a depending portion or elbow 11. An outlet pipe 12 is provided at the lower end of the casing for the water, and arranged within this outlet pipe, 50 and directly below the center of the hopper shaped bottom of the casing, the pipe 12 is

provided with a drain plug 13, for permitting sediment to be withdrawn from the pipe. A filling port 14 is provided at the top of the casing, the said port being normally closed by a threaded cap 15, and a valve 16 is provided in connection with the casing at the desired water level.

In use, the water is retained in the casing at the level of the valve 16, and water is supplied to the casing from the pump of the engine. This water is delivered on to the deflector or divider 7, which spreads it in a thin sheet over the screen. When air is withdrawn from the casing by the suction of the engine, through the pipe 4, air rushes in through the pipe 5, passing upward and out at the top of the said pipe. This air is deflected downwardly, and passes through the screen and through the stream of falling water which covers the outer face of the wire mesh screen 8. All sediment and impurities are strained out, so that the air passing through the carbureter is free from such impurities, and the wear and friction caused by dust and grit is eliminated.

I claim:

1. A device of the character specified, comprising a casing having an air outlet pipe at its top and an air inlet pipe at its bottom, said inlet pipe having an upward extension delivering at the axis of the casing, a shell supported in the casing in spaced relation and coaxial therewith through which the inlet pipe extends, a conical deflector above the delivery end of the inlet pipe, a screen connecting the lower larger end of the deflector to the upper end of the shell, a water supply pipe delivering at the apex of the deflector, a screen connecting the lower end of the shell to the casing, and a water outlet pipe at the bottom of the casing, said pipe having a drain opening, and a plug normally closing the opening.

2. A device of the character specified, comprising a casing having an air outlet pipe at its top and an air inlet pipe at its bottom, said inlet pipe having an upward extension delivering at the axis of the casing, a shell supported in the casing in spaced relation and coaxial therewith through which the inlet pipe extends, a conical de-

deflector above the delivery end of the inlet pipe, a screen connecting the lower larger end of the deflector to the upper end of the shell, and a water supply pipe delivering at 5 the apex of the deflector.

3. A device of the character specified, comprising a shell, an inlet pipe extending

into the shell, a conical deflector above the discharge end of the inlet pipe, a screen connecting the lower end of the deflector to the 10 shell, a water supply delivering on to the deflector, and a casing for the water inclosing the shell and deflector.

WALTER BIBBEE.
